(57) CLAIM

The ornamental design for a deck frame hanger, as shown and described.

DESCRIPTION

FIG. 1 depicts a perspective view of a deck frame hanger showing our new design according to a first embodiment.

FIG. 2 depicts a front view thereof.

FIG. 3 depicts a back view thereof.

FIG. 4 depicts a right side view thereof.

FIG. 5 depicts a left side view thereof.

FIG. 6 depicts a top view thereof.

FIG. 7 depicts a bottom view thereof.

FIG. 8 depicts a perspective view of a deck frame hanger showing our new design according to a second embodiment.

FIG. 9 depicts a front view thereof.

FIG. 10 depicts back view thereof.

FIG. 11 depicts a right side view thereof.

FIG. 12 depicts a left side view thereof.

FIG. 13 depicts a top view thereof.

FIG. 14 depicts a bottom view thereof.

FIG. 15 depicts a perspective view of a deck frame hanger showing our new design according to a third embodiment.

FIG. 16 depicts a front view thereof.

FIG. 17 depicts back view thereof.

FIG. 18 depicts a right side view thereof.

FIG. 19 depicts a left side view thereof.

FIG. 20 depicts a top view thereof; and,

FIG. 21 depicts a bottom view thereof.

The broken lines depict portions of the deck frame hanger that form no part of the claimed design.

CERTIFICATE OF CORRECTION

PATENT NO. : D1,032,335 S
APPLICATION NO. : 29/831896
DATED : June 25, 2024
INVENTOR(S) : Elijah R. Johnson, Eric Wehrli and Roger Edwin Winter

Page 1 of 2

It is certified that error appears in the above-identified patent and that said Letters Patent is hereby corrected as shown below:

On the Title Page

IN THE DESCRIPTION

Please remove the descriptions for FIGs 15-21 found at about lines 15-22.

Delete the title page and substitute therefor with the attached title page showing the corrected number of drawing sheets.

In the Drawings

Please delete Figures 15-21 found on sheets 7-9.

Signed and Sealed this
Twenty-eighth Day of January, 2025

Coke Morgan Stewart
Acting Director of the United States Patent and Trademark Office
